UNITED STATES PATENT OFFICE.

WILLIAM F. HART, OF PITTSBURGH, PENNSYLVANIA, ASSIGNOR TO VERONA TOOL WORKS, OF PITTSBURGH, PENNSYLVANIA, A CORPORATION OF PENNSYLVANIA.

RAIL BOND.

Application filed January 31, 1925. Serial No. 5,991.

The present invention relates broadly to bonds and more particularly to bonds adapted for use with railways and having generally resilient characteristics adapting them for being clamped in position between the webs of the rail ends to be bonded and the fish plates used for completing the joints.

It has heretofore been proposed to construct rail bonds of the general character herein disclosed of resilient material having rail web-engaging points, the body of the bonds being curved either longitudinally, transversely or both, to increase the strength of the bond and insure a better contact between the ends thereof and the webs of the rails.

As the bolts holding the fish plates in position are drawn up, the bonds are placed under a tremendous load having the effect of giving to the bonds a permanent set and of destroying their resiliency unless they are carefully constructed to meet all of the requirements imposed thereon. It will be apparent that the effectiveness of the bond established depends upon the resiliency of the material utilized, as in this manner the points can be more effectively driven into bonding relationship.

In some installations, the distance between bolt hole centers at the ends of the rails is comparatively short, thereby requiring the use of a bond having a small over-all length. In such installations, it will be apparent that proportionately the distance between the web of the rail and the inside of the fish plate or splice bar is much greater than in other installations, where the distance between the bolt hole centers is increased. By the present invention, there is provided a bond particularly adapted for use in installations where the bolt hole centers are close, although the utility of the invention is not limited in this respect and it is adapted for general application in the manner of bonds heretofore constructed.

In the accompanying drawings, I have shown for purposes of illustration only a preferred embodiment of the present invention, it being understood that the drawings do not define the limits of the invention, as changes may be made in the construction and operation disclosed without departing from the spirit of the invention or the scope of the broader claims. In the drawings:

Figure 1 is a sectional view through a portion of a rail joint showing my improved track bond in position;

Figure 2 is a side elevation of the construction illustrated in Figure 1, the fish plate being removed and the clamping bolts being shown in section;

Figure 3 is a perspective view of the bond;

Figure 4 is a transverse sectional view through the bond at substantially the center portion thereof; and

Figure 5 is a longitudinal sectional view through the bond.

Referring more particularly to Figures 1 and 2 of the drawings, there is shown a portion of a track joint comprising rail sections 70 2 and 3, the joint between which is bridged in the usual manner by fish plates or splice bars 4.

Between the center bolts 5 which hold the fish plates or splice bars in position, irrespective of whether the distance between the centers of these bolts is comparatively short or long, there is room for the insertion of a track bond which is constructed in accordance with the present invention. Such a bond will comprise a body of resilient material curved either longitudinally, transversely or both, the latter construction being illustrated in the drawings. The bond, however, apart from these general characteristics, is also preferably characterized in that it has an elongated hump 7, formed thereon. This hump is preferably of such construction that it provides an abrupt change in section in the bond with respect either to a transverse section as illustrated in Figure 4 or a longitudinal section as illustrated in Figure 5. Where the bond has its main body portion curved transversely, a transverse sectional view through the central portion of the bond will be characterized by 90 intersecting curved portions 8 of one radius and intersecting curved portions 9 of a different radius. In longitudinal sectional view the bond will be characterized by having a curved portion constituting the main body 100 of one radius and having a curved portion constituting the elongated hump of a different radius, it being assumed that the bond, as a whole, is provided with a longitudinal curvature.

I have found by actual tests that a bond having an elongated hump, whether the main portion of the bond be transversely curved,

longitudinally curved, or both, has its resistance to compression materially increased. This is particularly true in a bond having its main body portion curved both transversely and longitudinally. In such a bond, approximately three times as much pressure is required to compress the bond one-quarter of an inch as compared to that required to compress a bond which is only curved transversely and longitudinally without the elongated hump.

The advantages of the present invention arise from the provision of a bond of the general character herein referred to having at least a portion of its body disposed out of the plane of the remainder thereof, to provide a

projecting hump preferably of elongated configuration.

I claim:

1. As an article of manufacture, a rail bond comprising a body portion arched in all directions, and means located at the crown of said body portion for resisting compression thereof.

2. A rail bond comprising a spring plate curved laterally and longitudinally, said plate having a projection extending from the convex face thereof.

In testimony whereof I have hereunto set my hand.

WILLIAM F. HART.
